GUN MOUNTING

George H. Lazarus, Jr., and Jess F. Bewley,
Bowling Green, Ky.

Application February 11, 1942, Serial No. 430,452

10 Claims. (Cl. 89—37)

1

The present invention relates to an ordnance pointing mechanism, and more particularly to a device whereby relatively large caliber guns or cannon may be readily pointed and fired at short ranges with the same ease that at present characterizes the pointing and firing of an ordinary rifle.

Conditions of modern warfare have made it necessary that relatively large caliber guns be fired at point blank ranges, and that the same be pointed quickly enough to follow a swiftly moving object such as a tank or low flying plane.

In the copending application, Ser. No. 403,750, filed July 23, 1941, there is described a mechanism consisting in general of a gun mount or support adapted to receive a relatively heavy or large caliber gun which may be a machine gun or light cannon, and a second mount for a pointing piece which may be an actual rifle or a piece simulating an actual rifle.

The copending application referred to discloses a mechanism upon which the two guns described can be mounted and readily moved in vertical and horizontal planes with a minimum of frictional resistance.

In addition, there is disclosed in the copending application means whereby the large caliber gun will be made to follow the movement of the smaller rifle or pointing piece so that the gunner can aim the pointing piece and simultaneously fire the large gun at an object.

The present application relates to an improved mechanism of a type similar to that shown in the copending application, which can be more easily pointed, and which can be held more steadily under conditions of rapid fire.

One of the objects of the present invention, therefore, is the provision of a gun mounting mechanism which is capable of supporting a pointing piece, and a relatively large caliber gun in which both the pointing piece and large caliber gun are so supported that the large caliber gun can be held still under conditions of rapid fire.

A second object of the present invention is to provide in combination with a pointing piece and mounting means therefor, a cradle adapted to support a large caliber gun such as a 50 caliber machine gun, or the like, said cradle being so suspended that the center of fire of the large caliber gun is substantially aligned with the horizontal pivots for the cradle.

A third object of the present invention is to provide a pointing mechanism for a relatively large caliber gun which includes a pointing piece

2

mounted for relatively frictionless pivotal movement in both horizontal and vertical planes, and a relatively heavy caliber gun which is similarly mounted for relatively frictionless pivotal movement in horizontal and vertical planes, both the pointing piece and heavy caliber gun being adapted to be simultaneously moved as a unit even though the pointing piece is located at a substantial distance and at various positions relative to the heavy gun.

A fourth object of the present invention is to provide a mounting cradle for a relatively heavy caliber gun, which is supported for relatively frictionless movement in vertical and horizontal planes, and which is provided with a counterbalancing weight to vary the moment of the cradle and gun supported thereby about a vertical axis.

A fifth object of the present invention is to provide a pointing mechanism of the character described in which a pointing piece is located directly above a heavy caliber gun, and means are provided to move the heavy caliber gun in a manner corresponding to movements of the pointing piece.

A sixth object of the present invention is to provide in a device of the character described a pointing piece which is located below a heavy caliber gun which is coupled to the pointing piece so that movements of the pointing piece will simultaneously move the heavy caliber gun.

A seventh object of the present invention is to provide a ball bearing mounting for a heavy caliber gun which will enable the same to be moved with a minimum amount of friction in a pivotal manner in both horizontal and vertical planes, while maintaining the same in a balanced relationship relative to the center of fire thereof.

An eighth object of the present invention is the provision of a gun mount for a relatively heavy caliber gun which will enable the gun to fire a relatively concentrated cone of fire of a minimum dimension.

A ninth object of the present invention is to provide a gun mount for a machine gun or the like, wherein the gun may be balanced to produce a cone of fire of a relatively small height which may be adjusted either downwardly or upwardly from a base line.

A tenth object of the present invention is to provide a novel gun mount including a cradle in which the gun is floated or suspended, said gun being inherently balanced in said cradle to permit minimum natural vertical movement.

An eleventh object of the present invention is to provide a gun mount in which a gun is suspended or floated for relatively frictionless movement, and in which the gun may be balanced in any normal angular position relative to the horizontal.

A twelfth object of the present invention is to provide a support for a gun cradle which extends angularly from a base member so that the cradle and gun supported thereby may be moved through a greater angle of vertical fire, said support at the same time being of a compact construction.

Other objects and advantages of the present invention will become apparent from the subsequent description and figures of the drawings wherein:

Figure 1 is a rear elevation of a supporting structure for a pointing piece and heavy gun in accordance with the present invention.

Figure 2 is a plan view of the supporting structure of Figure 1.

Figure 3 is a section taken along the line 3—3 of Figure 2.

Figure 4 is a vertical section taken along the line 4—4 of Figure 1.

Figure 5 is a detail of the balancing weight assembly.

Figure 6 is a rear elevation of a gun supporting structure wherein the pointing piece is located above the heavy caliber gun.

Figure 7 is a detail of the tie rod connection for the construction of Figure 6.

Figure 8 is a rear elevation of a second modified form of the invention wherein the pointing piece is located below the heavy gun.

Figure 9 is a modified form of a supporting cradle for the heavy gun.

Figure 10 is a detail in section of one of the ball and socket joints connecting the tie rod and base plates of the guns.

Figure 11 is a diagrammatic illustration of the cone of fire of a gun mounted according to the present invention.

Referring to the drawings, and particularly Figures 1 to 3 thereof, there is here shown a pointing piece which is indicated in general at 10 which is suitably supported and fastened to base plate 11. The base plate 11 is in turn bolted as by bolts 12 to an outer housing 13 of a taper roller bearing assembly indicated in general at 13a, of a conventional design which is shown in detail in Figure 3. A stub shaft 14, forming a part of the roller bearing assembly is welded or otherwise suitably joined to a stub shaft 15 which is perpendicularly disposed relative to the shaft 14. Each end of the shaft 15 is suitably supported as by ball bearings 16 and 17. The bearings 16 and 17 are in turn supported by a U-shaped bracket indicated in general at 18. The bracket 18 is provided with two vertically disposed legs 19 and 20 which are bolted to the outer portions of the ball bearings 17 and 16, respectively.

The base of the U-shaped bracket is supported on a standard 21 and is shown particularly in the drawing as fastened to the standard by a pair of bushings 22 and 23, and nuts 24 and 25.

The standard 21 is immovably supported in a sleeve 26 in turn supported by a plurality of rods 27, 28 and 28a, the rods 28 and 28a being welded to a bracket 29 which is in turn welded to a main standard 30 rotatably supported at 30a. The rod 27 is welded to a bracket 31 which is bolted to the main standard 30 as by bolts 32.

It will be noted from the foregoing that the rifle or pointing piece 10 is therefore securely supported, but is nevertheless capable of pivotal movement in any horizontal or vertical plane. The ball bearing 13a serves as a vertical pivot for horizontal pivotal movements of the pointing piece 10, and the ball bearings 16 and 17 serve as a pivotal mounting for both the bearing 13a and the pointing piece 10 so that the pointing piece can be pivoted in a vertical plane about the bearings 16 and 17 as horizontal pivots.

Extending from the shaft 15 through the ball bearing 17 is the rotatable member 33 forming one end of a universal joint indicated in general at 34. The other end of the universal joint is rotatable with a shaft 35 which is in turn connected to a second universal joint indicated in general at 36. As shown in Figure 1, the universal joint 36 is in turn connected and rotatable with a pivot indicated in dotted lines at 37. The pivot 37 is rotatably mounted within a ball bearing indicated in general at 38. The righthand end of the pivot 37 in turn supports an arm 39 which forms one of the upright legs of a U-shaped bracket including the arm 39, a base portion 40 and a second arm 41. The two arms 39 and 41 are bolted to the base portion 40 as by bolts 42 and 43. The arm 41 is supported by a pivot indicated in dotted lines at 44. The pivot 44 is in turn rotatably mounted in a ball bearing indicated in general at 45.

It is evident therefore from the foregoing that the U-shaped bracket comprising the base 40 and the arms 39 and 41 is pivoted for movement in a vertical plane by means of the two pivots 37 and 44, and as will be hereafter described, forms a cradle for a relatively heavy caliber gun. The pivot 44 also carries at the end thereof from the arm 41 a counterbalancing weight 46. The weight 46 is bolted as by a bolt 47 to an arm 48 which is provided with a hub 49 mounted on the pivot 44. Set screws 50 extend through the hub 49 into the pivot 44, and prevent relative rotation therebetween.

The arm 48, as shown in Figure 5, is provided with a plurality of holes 51 into which the bolt 47 is adapted to enter in order to enable the weight 46 to be moved upwardly or downwardly upon the arm 48. The weight 46 may therefore be positioned closer or farther away from the hub 49, and the entire hub assembly may be rotated relative to the pivot 44 by loosening the set screws 50, and thereafter tightening the same. The weight 46 therefore acts as a variable balancing means for the U-shaped bracket or cradle previously described, as well as for the heavy gun which is supported thereby.

A tapered roller bearing assembly is indicated in general at 52 upon the base 40. The roller bearing assembly 52 is adapted to rotatably support as by its outer portion 53, a base member 54 of a mount indicated in general at 55 for supporting a relatively heavy caliber gun.

The mount shown in the specific embodiment of the invention is particularly adapted to support a standard .50 caliber machine gun, but it is to be understood that a mount for any relatively heavy caliber gun may be substituted therefor.

As shown, the mount consists of a pair of side plates 56 and 57 each extending from the member 54, and connected at their forward and rearward ends by a pair of bolts 58 and 59. A plurality of holes indicated at 60 in Fig. 4 are provided in the side plates to which the machine gun may be bolted. At their forward end, the side

plates 56 and 57 are connected by a horizontal plate-like member 61, having a forward extension 62. The front end of the extension 62 is provided with a pin 63 which is journaled within an end of a shaft or rod 64 so as to support the same, and at the same time permit the rotation of the rod 64 relative to the pin 63. The rod 64 is connected by means of a turnbuckle 64a with a second rod 65 which is rotatably connected to the forward end of the base plate 11 for the pointing piece previously described.

It is to be understood that the connection of the rod 65 and the base plate 11 is similar to the connection of the portion 62 and the rod 64 so that the rod 65 is capable of rotation relative to the base plate 11.

It is evident that by turning the turnbuckle 64a the forward end of the plate 11 and the forward end 62 of the plate 61 can be brought closer together or moved farther apart. Since as previously described, the plate 11 supports the pointing piece 10, and the plate 61 connects the side plates 56 and 57 which form a portion of the supporting means for the machine gun which is indicated in general at 66 in Figure 1, that when the plate 62 and the plate 11 are brought together, the front ends of the pointing piece and the gun will be brought closer together. This arrangement enables the pointing piece and gun to point at the same mark.

The function of the rods 64 and 65 together with the turnbuckle 64a is to couple the forward ends of the pointing piece and machine gun so that when the pointing piece is moved or pivoted in any horizontal direction, the machine gun will follow the movement thereof, it being understood that the machine gun pivots on the bearing 52, and the pointing piece on the bearing 13a. The machine gun also follows vertical pivotal movement of the pointing piece 10.

As previously pointed out the shaft 15 is coupled to the pivot 37 by means of universal joints 34 and 35 in the shaft 35. Movement of the pointing piece 10, therefore, about the ball bearings 16 and 17 will similarly move the machine gun 66 about the ball bearings 38 and 45.

It is to be noted that the ball bearings 38 and 45 are supported on a U-shaped member 67 which is bolted as by the bolts 68 to the top of the main standard 30.

Referring particularly to Figures 4 and 5 of the drawings, it will be noted that the side arms of the U-shaped member 67 extend angularly rearwardly from the base member 30. This enables the gun to be tilted upwardly through a greater angle of fire. By thus offsetting the pivots relative to the base member 30 the U-shaped member 67 may be made relatively small and at the same time, the gun may be pivoted in a vertical plane until it points almost directly upwardly. This would not be possible without the offset construction, since the rear end of the gun or the support therefor would contact the bottom of the U-shaped bracket 67 before the gun had been elevated any substantial amount.

Referring to Figure 1, it will be noted that the base member 30 is supported by a bearing 30a. This enables the entire base member 30 and both the gun and pointing piece to be swung through 360°.

Referring to Figures 6 and 7, there is here shown a modified device in which the heavy caliber gun or machine gun is mounted directly upon a main standard 69, and the pointing piece is mounted above the machine gun.

Referring to Figure 6, in particular, there is here shown a bracket member 70 which is supported on the upper end of the main standard 69 as by a tapered roller bearing 71 so that the bracket 70 is rotatable relative to the standard. Supported by the bracket 70 as by ball bearings 72 and 73 are a pair of pivot members 74 and 75. The pivot members 74 and 75 in turn pivotally support a U-shaped bracket 76 which forms a cradle for the machine gun or other heavy caliber weapon indicated in general at 77.

The support for the gun 77 consists of a pair of side plates 78 and 79 similar to the plates 56 and 57 of Figure 1 which are connected by a base plate 80 which is firmly bolted to the bracket 76 as by bolts 81. It is evident, therefore, that the machine gun 77 is capable of pivotal movements in a horizontal plane about the ball bearing 71, and at the same time can be pivoted in a vertical plane about the ball bearings 72 and 73.

Firmly fixed to the top of the bracket 70 as by bolts 82 is a shaft 83, which is firmly fixed at its upper end to a U-shaped bracket 84. The shaft 83 is also rotatably supported by a tapered roller bearing 85 carried by an arm 86 which is firmly fixed to the main standard 69 by a bracket 87. The U-shaped bracket 84 forms a support for the pointing piece indicated at 88. The bracket 84 supports a pair of ball bearings 89 and 90 in which the stub shaft 91 is rotatably journaled. The shaft 91 is welded to a vertical shaft 92 which is bolted to a supporting plate 93 for the gun 88 as by bolts 94.

In this modification of the invention, the forward end of the pointing piece 88 and the large caliber gun 77 are joined by a rod assembly including a pair of rods 95 and 96 and a turnbuckle 97. The rod 96 is connected to the gun 88 as by a ball and socket joint 98, and the rod 95 is connected to the gun 77 as by a ball and socket joint 99. The rod assembly, therefore, consisting of the rods 95 and 96 and the turnbuckle 97 will produce similar movements in a vertical plane of the pointing piece 88 and the gun 77, the pointing piece 88 being pivoted for this movement about the bearings 89 and 90, and the gun 77 being pivoted for this movement about the bearings 72 and 73. Through the shaft 83, the gun 77 will also follow horizontal pivotal movements of the pointing piece 88, the entire assembly for both guns being pivoted about the bearings 71 and 85.

Referring to the modification of the invention shown in Figure 8, it will be noted that the relatively large caliber gun here indicated at 100 is supported above the pointing piece indicated at 101. The supporting means for the pointing piece 101 includes a plate 102 to which the gun is suitably affixed, the plate 102 being bolted to a collar 103 which is carried on a vertical stub shaft 104 welded to the horizontal shaft 105. The shaft 105 is rotatably mounted at each end in the ball bearings 106 and 107. The ball bearings 106 and 107 are in turn carried by a frame 108 which is rotatably mounted in the tapered roller bearing indicated in general at 109 which is mounted on top of the main standard 110.

It is evident, therefore, that the pointing piece 101 is mounted for pivotal movement in a vertical plane about the axis of the bearings 106 and 107, and is mounted for pivotal movement in a horizontal plane about the axis of the bearing 109. A crank 111 connects the frame 108 to a shaft 112 which is supported by a tapered roller bearing indicated in general at 113. The roller bearing 113 is supported by an arm 114 which is

affixed to a bracket 115, also mounted immovably on the standard 110.

It is evident, therefore, that rotational movement of the pointing piece 101 in a horizontal plane will similarly move the shaft 112. The shaft 112 is in turn affixed as by a collar 116 to a U-shaped bracket 117. The bracket 117 supports at its upper ends the ball bearings 118 and 119. Pivots 120 and 121, indicated in dotted lines in Figure 8, are journaled for rotation within the ball bearings 118 and 119, respectively. A U-shaped cradle 122 is mounted within the U-shaped bracket 117 to rotate with the pivots 120 and 121.

Carried on the cradle 122 and bolted thereto is the support proper indicated in general at 123 for the gun 100. It is evident, therefore, that when the shaft 112 rotates to move the bracket 117, the gun 100 will be moved similarly therewith. However, the gun 100 will be also capable of rotating movement in a vertical plane about the axis of the ball bearings 118 and 119. The forward end of the gun 100 and the pointing piece 101 are coupled together with a rod and turnbuckle assembly in a similar manner to that shown in connection with the modification of Figure 7.

It will be noted, therefore, from the foregoing that when the pointing piece 101 is moved in either a horizontal or vertical plane, the gun 100 will follow the movement thereof.

In Figure 9, there is disclosed a modified cradle support for a relatively heavy gun which may be utilized in any of the modifications just hereinbefore disclosed, or used by itself as a mounting for a heavy gun. A standard 124 is here shown which carries a U-shaped bracket 125 supported thereon as by a tapered roller bearing 125a. The bracket 125 supports a pair of ball bearings indicated in general at 126 and 127. Rotatably within the bearings 126 and 127 are a pair of movable pivots 128 and 129 respectively which are indicated in dotted lines. Movable with the pivots is a rectangularly shaped cradle 130 which serves to support at its upper and lower ends a second pair of tapered roller bearings 131 and 132. Rotatably mounted within the tapered roller bearings 131 and 132 are a pair of vertical pivots 133 and 134. Mounted to rotate with the pivots 133 and 134 is a second cradle member 135. A support for a relatively large caliber gun indicated in general at 136 is affixed on the inner cradle 135 and supported on a suitable conventional support indicated in general at 137.

It will be evident, therefore, that the gun 136 mounted in the two cradles 135 and 130 will be capable of relatively frictionless motion in both horizontal and vertical planes. Thus, when the gun is moved in a horizontal plane, it will pivot about the axis of the roller bearings 131 and 132. Similarly, when it is moved in a vertical plane, it will pivot about the axis of the bearings 126 and 127.

This particular cradle differs from the heavy gun cradles previously described in that it is supported both at its upper and its lower end, and the center of fire thereof is therefore more accurately positioned in alignment with the center of support in both a vertical and horizontal manner. It is obvious that a gun so mounted may be moved when a pointing piece is moved, by providing a linkage similar to that shown in Figure 1.

It is to be noted in particular that in each of

the modifications described, the heavy gun is so mounted that the center of fire thereof is in horizontal alignment with the pivots upon which the entire cradle rotates for vertical pivotal movement. This arrangement prevents rapid fire of the gun from imparting a turning moment to the heavy gun carriage and enables the gunner to more easily maintain both the pointing piece and the heavy gun in position. The counterbalancing weight 46 may also be adjusted to assist in balancing the movement in any desired position; for example, in some instances it may be desirable that the heavy gun and pointing piece be disposed so as to point slightly upwardly, as for example when the gun is being used against dive bombers. In this instance it is desirable that the weight 46 be located to the rear of the center of pivot of the heavy gun. As previously pointed out, the weight can be shifted by loosening the set screws 50 and by rotating the entire arm 48 about the pivot 44.

Referring to Figure 10, there is here shown in detail the ball and socket joint which connects the end of the rod 64 with the member 62. As shown, the pin 63 extending from the member 62 is provided at its lower end with a ball 138 which is received in a socket formed by the cup 139 and the movable cup 141. The first cup 139 is welded into the rod 64 as indicated at 140 or may be otherwise securely fastened within the hollow rod 64. A set screw 142 bears on the movable cup 141 and serves to firmly secure the ball within the socket.

Referring to Figure 11, there is diagrammatically represented shot pattern produced on a target by a normal cone of fire of a machine gun in an average modern mount indicated at 143, and the cone of fire pattern which has been produced with the present gun mount indicated at 144 and 145.

It will be noted that the standard cone of fire pattern 143 is of a height indicated by the line 146, and that the line 147 measuring the height of the cone of fire pattern 144 is approximately $\frac{1}{5}$ or $\frac{1}{6}$ the height of the normal cone of fire pattern.

By shifting the gun 66 of Figure 1 forwardly in its cradle, it may be made to shoot a cone of fire indicated at 145 below the base line 148. It is for this purpose that the various holes 60 shown in Figure 4 are provided.

This effect is believed to be produced because a gun in the mount of the present invention, instead of being suspended in a relatively fixed manner is floated in a relatively frictionless mount and is then balanced within the mount so that it does not tend to move either upwardly or downwardly. Since the centers of its vertical suspension are in horizontal alignment with the center of fire, even the firing of the gun does not tend to draw the gun upwardly as in the normal mount.

It is desired to point out that the cone of fire indicated at 145 is but slightly larger than the effect produced by the barrel whip of a normal machine gun.

It is further desired to point out that the present mount is especially well adapted to support a plurality of relatively heavy guns shooting in tandem. Thus, in the mount shown in Figure 1, instead of a single .50 caliber machine gun indicated at 66, a plurality of guns mounted either side by side or one above the other may be used, and all of the guns will be moved when the pointing piece 10 is moved. Alternatively, a plurality

of mounts for the heavy gun may be arranged side by side, each incorporating all of the elements of the heavy gun mount shown. Each of these guns may then be moved from the pointing piece 10 by connecting the pointing piece to each of these guns by a shaft such as the shaft 35. Where, in the claims, therefore, a heavy caliber gun is described, it is to be understood that a plurality of guns may thus be indicated.

The present application and application Serial No. 403,750, filed July 23, 1941, contain common subject matter, some of the claims in the present application being readable on said common subject matter.

Having thus described the invention, we claim:

1. In a gun assembly, a pointing piece, a gun, primary means for supporting said gun for free pivotal movement in an horizontal plane, a second means for suspendedly supporting said gun in a vertical plane for substantially frictionless movement comprising a plurality of anti-friction bearings, a pair of pivots rotatably mounted therein, an offset supporting member for said bearing and pivots, a cradle pivotally mounted on said pivots, said cradle including a pair of arms extending downwardly from said pivots, an horizontal supporting base connecting the lower ends of said arms, a gun mount rotatably mounted on said supporting base, a support for said pointing piece disposed laterally of said primary support means, anti-friction bearings mounted on said lateral support means, pointing-piece pivots supported on anti-friction bearings, said pointing-piece suspendedly mounted on said pivots for substantially frictionless movement, and means for connecting said gun and said pointing-piece whereby sighting movement of said pointing-piece will simultaneously move said gun.

2. In a gun assembly, a pointing piece, a gun, primary means for supporting said gun for free pivotal movement in an horizontal plane, a second means for suspendedly supporting said gun in a vertical plane for substantially frictionless movement comprising a plurality of anti-friction bearings, a pair of pivots rotatably mounted therein, an offset supporting member for said bearing and pivots, a cradle pivotally mounted on said pivots, said cradle including a pair of arms extending downwardly from said pivots, a horizontal supporting base connecting the lower ends of said arms, a roller bearing member rotatably mounted on said horizontal supporting member, an horizontally extending base member mounted on the roller bearing member, spaced oppositely positioned side members extending upwardly from said latter base member, means for fastening said side members together at their forward and rear ends, means for fastening the gun to said side members, an extension support secured to the side members at the forward end thereof, an extension member projecting therefrom, means thereon for rotatably mounting therein a shaft member, said side members and their assemblage of elements forming a gun mount; a support of said pointing piece disposed laterally of said primary support means, anti-friction bearings mounted on said lateral support means, pointing-piece pivots supported by anti-friction bearings, said pointing-piece suspendedly mounted on said pivots for substantially frictionless movement and means for connecting said gun and said pointing-piece so that sighting movement of said pointing-piece will simultaneously move said gun.

3. In a gun assembly, a pointing piece, a gun,

primary means for supporting said gun for free pivotal substantially frictionless movement in an horizontal plane for substantially frictionless movement, a second means for suspendedly supporting said gun in a vertical plane comprising a plurality of anti-friction bearings, a pair of pivots rotatably mounted therein, an offset supporting member for said bearing and pivots, a cradle pivotally mounted on said pivots, said cradle including a pair of arms extending downwardly from said pivots, a horizontal supporting base connecting the lower ends of said arms, a roller bearing member rotatably mounted on said horizontal supporting member, an horizontally extending base member mounted on the roller bearing member, spaced oppositely positioned side members extending upwardly from said latter base member, means for fastening said side members together at their forward and rear ends, means for fastening the gun to said side members, an extension support secured to the side members at the forward end thereof, an extension member projecting therefrom, a pin thereon having means for rotatably mounting therein a shaft member, said side plates and their assemblage of elements forming a gun mount; a support for said pointing piece disposed laterally of said primary support means, anti-friction bearings mounted on said lateral support means, pointing-piece pivots supported by anti-friction bearings, said pointing-piece suspendedly mounted on said pivots for substantially frictionless movement, and means for connecting said gun and said pointing-piece so that sighting movement of said pointing-piece will simultaneously move said gun.

4. A gun and pointing assembly comprising a standard, a supporting frame on the standard, a cradle pivotally mounted on the frame for free pivotal substantially frictionless movement in a vertical plane, a gun mount pivotally supported on the cradle for free pivotal substantially frictionless movement in a horizontal plane, a gun secured to said mount and partaking of said cradle and mount movements, means extending laterally from the standard and connecting the standard to a pointing unit, means carried by the outer end of said laterally extending means to support a pointing member, a pointing assembly mounted on said latter means including a pointing piece and a mount therefor, said mount for the pointing piece being constructed and arranged to provide pivotal substantially frictionless movements in vertical and horizontal planes, and means for connecting said gun and pointing piece so that the sighting movement of said pointing piece will simultaneously move said gun.

5. A gun and pointing assembly comprising a standard, a supporting frame on the standard, a cradle pivotally mounted on the frame for free pivotal substantially frictionless movement in a vertical plane, a gun mount pivotally supported on the cradle for free pivotal substantially frictionless movement in a horizontal plane, a gun secured to said mount and partaking of said cradle and mount movements, means extending laterally from the standard and connecting the standard to a pointing unit, means carried by the outer end of said laterally extending means to support a pointing member, a pointing assembly mounted on said latter means including a pointing piece and a mount therefor, said mount for the pointing piece being constructed and arranged to provide pivotal substantially frictionless movements in vertical and horizontal planes, a tie member between said gun and point-

ing piece mounts to cause one to follow the horizontal plane movement of the other, and a universal shaft connection between the pointing piece mount and the cradle to cause the cradle to follow vertical plane movements of the pointing piece, and means for connecting said gun and pointing piece so that the sighting movement of said pointing piece will simultaneously move said gun.

6. A gun and pointing assembly comprising a standard, a supporting frame on the standard, a cradle pivotally mounted on the frame for free pivotal substantially frictionless movement in a vertical plane, a gun mount pivotally supported on the cradle for free and substantially frictionless movement in a horizontal plane, a gun secured to the mount and partaking of said cradle and mount movements, a brace structure extending laterally from the standard and connecting the standard to a pointing unit, a sleeve carried by the outer end of the brace structure to support a pointing member, a pointing assembly mounted on said sleeve including a pointing piece and a mount therefor, said mount for the pointing piece being constructed and arranged to provide pivotal and substantially frictionless movements in vertical and horizontal planes, and means for connecting said gun and pointing piece so that the sighting movement of said pointing piece will simultaneously move said gun.

7. A gun and pointing assembly comprising a standard, a supporting frame on the standard, a cradle pivotally mounted on the frame for free pivotal substantially frictionless movement in a vertical plane, a gun mount pivotally supported on the cradle for free and substantially frictionless movement in a horizontal plane, a gun secured to the mount and partaking of said cradle and mount movements, a brace structure extending laterally from the standard and connecting the standard to a pointing unit, a sleeve carried by the outer end of the brace structure to support a pointing member, a pointing assembly mounted on said sleeve including a pointing piece and a mount therefor, said mount for the pointing piece being constructed and arranged to provide pivotal and substantially frictionless movements in vertical and horizontal planes, a tie member between said gun and pointing piece mounts to cause one to follow the horizontal plane movement of the other, and a universal shaft connection between the pointing piece mount and the cradle to cause the cradle to follow vertical plane movements of the pointing piece, and means for connecting said gun and pointing piece so that the sighting movement of said pointing piece will simultaneously move said gun.

8. A gun and pointing assembly comprising a standard, a supporting frame on the standard, a cradle pivotally mounted on the frame for free pivotal substantially frictionless movement in a vertical plane, said frame being provided with horizontally spaced bearings, trunnions on the cradle journalled in said bearings, a gun mount pivotally supported on the cradle for free and

substantially frictionless movement in a horizontal plane, a gun secured to the mount and partaking of said cradle and mount movements, a brace structure extending laterally from the standard and connecting the standard to a pointing unit, a pointing and sighting assemblage mounted on the outer end of the brace structure and including a pointing piece and a mount therefor, means including a shaft to cause said pointing piece mount to move substantially frictionlessly in vertical and horizontal planes, a tie member between said gun and pointing piece mounts to cause one to follow the horizontal plane movements of the other, and a shaft provided with universal connections with the shaft of the pointing piece mount and one trunnion of the gun mount.

9. A gun and pointing assembly comprising a support, a frame on the support, said frame having vertical side members, bearings in said side members, a gun supporting cradle provided with lateral trunnions disposed in said bearings, said cradle being pivotally mounted on said bearings for free pivotal substantially frictionless movement in a vertical plane, a gun mount pivotally supported on said cradle for free and substantially frictionless movement in a horizontal plane, a gun secured to the mount and partaking of said cradle and mount movements, a laterally offset pointing and sighting assembly supported on said support, said pointing and sighting assembly including a sighting piece and a mount therefor, said pointing piece mount being universally and frictionlessly movable, tie means between the gun and pointing piece assemblage, and a universal shaft connection between the pointing piece mount and one trunnion of the gun cradle to cause the cradle to swing proportionately with the corresponding movement of the sighting piece.

10. A gun and pointing assembly comprising a support, a frame on the support, said frame having vertical side members, bearings in said side members, a gun supporting cradle provided with lateral trunnions disposed in said bearings, said cradle being pivotally mounted on said bearings for free pivotal substantially frictionless movement in a vertical plane, a gun mount pivotally supported on said cradle for free and substantially frictionless movement in a horizontal plane, a gun secured to the mount and partaking of said cradle and mount movements, a laterally offset pointing and sighting assembly supported on said support, said pointing and sighting assembly including a sighting piece and a mount therefor, said pointing piece mount being universally and frictionlessly movable, said gun mount and pointing piece mount being provided with opposed parallel extensions, tie means between the free end portions of said extensions and a universal shaft connection between the pointing piece mount and the cradle to cause the cradle to follow vertical plane movements of the pointing piece.
